UNITED STATES PATENT OFFICE.

EDWARD B. ALLEN, OF BRIDGEPORT, CONNECTICUT, ASSIGNOR TO THE SINGER MANUFACTURING COMPANY, A CORPORATION OF NEW JERSEY.

STITCH-FORMING MECHANISM FOR SEWING-MACHINES.

1,162,207.

Specification of Letters Patent. Patented Nov. 30, 1915.

Application filed October 5, 1914. Serial No. 865,039.

To all whom it may concern:

Be it known that I, EDWARD B. ALLEN, a citizen of the United States, residing at Bridgeport, in the county of Fairfield and State of Connecticut, have invented certain new and useful Improvements in Stitch-Forming Mechanisms for Sewing-Machines, of which the following is a specification, reference being had therein to the accompanying drawings.

This invention relates primarily to an improvement in overseaming stitch-forming mechanism and more particularly of that class embodied in eyelet buttonhole stitching machines in which the stitch-forming elements are mounted upon rotary supports disposed respectively above and below the work and provided with means for turning them in the stitching of the eyelet-end of the buttonhole.

The invention has for its principal object to provide the stitch-forming elements sustained upon a rotary turret beneath the work, and coöperating with a reciprocating needle, with actuating means adapted for operation at high speed and sustained mainly by the sewing machine frame independently of the rotary turret.

The lower stitch-forming elements preferably comprise an oscillatory and bodily reciprocating looper adapted to seize thread-loops from the needle in combination with a curved lower needle entering the loops thus seized from the needle and pass loops of its own thread upward through the work for descent of the upper needle through its thread-loop. The present invention is designed to provide crank-and-pitman actuating mechanism sustained independently of the turret and adapted to produce a dip of the lower needle in its upper position for presenting a loop of its thread to the upper needle, and to provide a quick movement of the looper for seizure of the upper-needle thread-loop for distention and passage through the same of the lower needle.

The invention has for a further object to provide a crank motion for the upper needle which shall be suitably timed for proper presentation of its thread-loops to the looper and which shall cause the needle to be retracted from the work for a sufficient interval not only to permit the feed of the work but to insure the retraction of both needles to extreme position at the completion of a

stitch-forming cycle for introduction and removal of the work.

The invention has for a further object to provide turning means for the stitch-forming elements which shall properly perform its function without interference with other parts of the mechanism in the adjustment or removal of the latter for repairs or for other purposes.

It has for a further object to provide driving means for the stitch-forming elements of such character that the machine may be stopped at the completion of each stitching period without undue shock and consequent liability to injury of the controlling stop-motion device.

In the preferred form of the improvement, the stitch-forming elements coöperating with the upper needle are mounted upon a lower rotary support or turret and are provided with simple connections with an axially reciprocating rod adapted to turn with the turret and having a swivel connection with one of the elements of a toggle device whose other element is connected by a link with an actuating crank of an intermediate shaft driven at double the speed of the main-shaft journaled in the base member of the machine frame. The head of the said reciprocating rod is provided with an internally grooved aperture forming a nut which is slidably fitted upon a spiral gear having rigidly connected therewith an actuating crank pivotally connected with the looper-carrier which is pivotally sustained at another point upon a swinging arm fulcrumed upon the turret. The looper is fixed upon its carrier and derives therefrom oscillatory movements upon said actuating crank and bodily reciprocating movements upon said swinging arm whereby it is caused to seize a thread-loop from the upper needle upon one side thereof and carry it around the same for passage of the lower needle in its ascent through the work for coöperation with the upper needle.

The curved and eye-pointed lower needle is fixed upon a substantially vertically swinging carrying arm mounted upon a fulcrum sustained by the turret at a slight inclination from the operative face of the work-holder or a plane perpendicular to the path of reciprocation of the upper needle, and said carrying arm has a link connection with the head of the reciprocating ac-

tuating rod from which it derives reciprocatory movements simultaneous with those of the looper, but differentially thereof.

A rotary upper shaft is preferably journaled in the bracket-arm of the machine frame to rotate in unison with the main-shaft and connected by a trammel device with the needle-actuating shaft carrying a crank connected by a pitman with a stud 5 sustained by and laterally offset from the axis of the upper needle-bar. By this means, the upper needle carried by the needle-bar is caused to reach its lower position slightly before its actuating crank reaches 10 its corresponding position from which it begins an early rising movement for presentation of its loop for seizure by the looper without shortening the normal period in which the feed takes place or the period in 15 which it remains above the work while the lower needle is retracted.

The rotary bushing for the upper needle and the turret are provided with the usual pinions meshing with toothed sectors which 20 are preferably mounted upon separate but aligned fulcra sustained respectively by the bracket-arm and the machine base, these toothed sectors having lateral arms connected by adjustable links with cranks upon a 25 vertical rock-shaft in the rearward portion of the frame which is operated by a connection with the feed-wheel for turning the stitch-forming elements in the stitching of the eyelet-end of the buttonhole. By the 30 means thus described, the toothed sectors may be made very rigid and light in weight, in that they are fulcrumed near the pinions which they operate, while ample space is given beneath the bracket-arm for installation 35 of the traveling work-holder and the buttonhole cutting mechanism without interference, while enabling the parts to be readily assembled and removed independently of the turning means for the stitch-forming 40 mechanism.

It is desideratum in machines designed for operation at high speed to reduce to the utmost the weight of moving parts whose momentum and inertia must be overcome in 45 stopping and starting the machine. According to the present improvement, the actuating devices for the stitch-forming elements are made as simple and regular in movement as practicable consistent with 50 rigidity and durability, and these devices have accelerating connections with the heavier portions of the operating mechanism which may thus be driven at a comparatively slow speed. By this means, the work 55 imposed upon the stop-motion is very materially reduced, and the time involved in bringing the mechanism up to full speed at the beginning of a buttonhole stitching operation is correspondingly reduced.

60 In the accompanying drawings, Figure 1

is a side elevation, partly in section, of an eyelet-buttonhole stitching machine of the general type represented in my United States Patent No. 1,048,786, of December 31, 1912, but containing stitch-forming mechanism of the type disclosed in the United States Patent of G. S. Hill No. 684,241, of October 8, 1901; Fig. 2 a bottom plan, and Fig. 3 a front end view of the same with certain unessential parts omitted. Fig. 4 is 75 a front end view of the parts of the machine below the work-holder at a different stage of the stitch-forming cycle from that disclosed in the preceding figure. Fig. 5 is a side elevation of the turning mechanism for the 80 stitch-forming devices. Fig. 6 is an elevation of a part of the lower needle mechanism and certain accessories. Fig. 7 is a perspective view of the looper-actuating rod. Figs. 8, 9 and 10 are perspective views showing the stitch-forming elements in different stages of their cycle of operation. Fig. 11 is an enlarged detail perspective view showing the looper in the act of seizing a thread-loop from the upper needle and Fig. 12 is a 90 similar view representing the lower needle about to pass through the upper-needle thread-loop held distended by the looper.

The machine frame corresponds with others of the same type in comprising the 95 hollow rectangular base 1 from which rises the hollow standard 2 having the tubular overhanging arm 3 terminating in the head 4. The base 1 is shown resting upon the bed-plate 5. Within the base 1 is suitably 100 journaled the main-shaft 6 provided with quartering cranks 7 connected by pitmen 8 with similar cranks 9 of the rotary upper shaft 10 journaled in the bracket-arm and provided at its rearward end with the hand-wheel 11. Upon the rear end of the main-shaft is loosely mounted the grooved belt-wheel 12 provided with the clutch-ring 13 forming one member of a stop-motion of which the coöperating spring-pressed tooth 110 14 is sustained by the lower arm of the stop-lever 15 mounted upon the fulcrum-pin 16 which is sustained by the bracket 17 projecting rearwardly from the base 1. This stop-motion is substantially the same in construction as that of my prior Patent No. 1,024,490, of April 30, 1912.

Upon the forward end of the shaft 10 is mounted the disk 18 having intersecting diametrical grooves 19 entered by roller-studs 120 20 of the disk 21 whose hub 22 is secured upon the needle-actuating shaft 23 which derives from the shaft 10, through the trammel device, comprising the disks 18 and 21, two rotations for each rotation of the shaft 125 10. The shaft 23 carries the crank-disk 24 having the crank-pin 25 connected by means of the pitman 26 with the laterally offset stud 27 of the collar 28 loosely embracing but restrained by the split collar 29 against 130

endwise movement upon the reduced upper portion of the reciprocating tubular needle-bar 30 which is disposed in axially intersecting relation with the shaft 23. The pitman connection of the crank-pin 25 with the needle-bar through the offset stud 27 is thus disposed at one side of a diameter of the circular path of movement of the crank-pin which is parallel with the needle-bar.

The needle-bar has its upper bearing in the bushing 31 of the bracket-arm head, and its lower bearing in the rotary support or bushing 32 journaled in the lower member of the bracket-arm head and provided at its lower end with the collar 33 from which depends the guide-arm 34 provided in its inner face with a channel entered by the stud 35 projecting laterally from the needle-clamp 36 carrying the eye-pointed straight needle 37. The bushing 32 is provided beneath the bracket-arm head with the toothed pinion 38 and has secured thereon above its bearing the collar 39 by which said bushing is maintained in position. The engagement of the stud 35 with the guide-arm 34 serves to maintain the needle-bar in fixed circular relation with its bearing bushing while permitting it to reciprocate freely therein.

The main-shaft has secured upon its forward end the gear-wheel 40 meshing with a toothed pinion 41 of one-half its diameter fixed upon the rearward end of the intermediate looper-actuating shaft 42 which has fixed upon its forward end the crank-arm 43 provided with the stud-pin 44. The stud or crank-pin 44 thus has, through the described connections, uniform rotary movements in unison with those of the needle-actuating crank-pin 25. The stud-pin 44 enters one apertured end of a link 45 connected at the opposite end by means of the screw-stud 46 with the swinging lever 47 whose lower apertured end is fulcrumed upon the stud-screw 48 sustained by the bracket-plate 1^b secured to the cross-member 1^a of the base 1.

To the free end of the lever 47 is pivotally attached by means of the screw-pin 49 the link 50 whose apertured opposite end is pivotally connected by means of the screw-pin 51 with the head 52 of the tubular reciprocating plunger-bar 53 journaled in a bearing boss 54 of the bracket-plate 1^b. As will be observed, the pivotally connected swinging members 47 and 50 constitute a toggle device of which the thrust of one member is received by the fixed fulcrum-stud 48 and that of the other member is imparted through the stud-pin 51 to the plunger-bar 53 which derives interrupted reciprocatory movements from the uniformly rotating crank 43 through such toggle device.

The laterally extending head 52 of the plunger-bar 53 is formed with a fork 52' entering an annular groove or neck 55 of

the tubular actuating rod 56 having at its upper end the laterally extending head 57. The rod 56 is journaled in the axially depending tubular hub 58 of the rotary disk 59 constituting the turret which sustains the lower stitch-forming elements. The hub 58 of the turret is journaled in a suitable aperture of the bearing boss 60 formed upon the bracket-plate 1^b and sustaining the curb 61 having secured upon the bottom of its cylindrical cavity the wearing plate 62 upon which the turret member 59 rests. The turret is confined in position upon said wearing plate by means of the toothed pinion 63 secured upon its hub 58 immediately beneath the same and housed within a suitable recess of the bearing boss 60.

Rigidly secured upon the disk 59 is the post 64 which is provided with a lateral arm terminating in a bearing boss 65 in which is journaled a short vertical rock-shaft 66 having secured thereon the spiral gear 67 whose lower end rests upon the disk 59. The gear 67 is slidingly fitted within the internally and spirally grooved aperture in the head 57 of the rod 56 from which it derives oscillatory movements from the vertical movements of said rod. The rock-shaft 66 carries a crank-arm 68 pivotally connected by means of the screw-pin 69 with the rocking looper-carrying block 70.

Upon the block 70 is adjustably secured by means of the fastening screws 71 the shank 72 of the looper formed with the beak 73 having at its base the depending lip 74 forming therewith a throat for reception of the needle-thread loops entered by the beak. The looper-carrier is pivotally mounted by means of the screw-pin 75 upon the outer end of the swinging arm 76 which is provided at its other end with the fulcrum-pin 77 journaled in the bearing boss 78 sustained by a second lateral arm of the post 64.

Secured upon the disk 59 is a second post 79 formed at its upper end with the slightly inclined bearing boss 80 in which is journaled the laterally projecting fulcrum screw-stud 81 extending from the base of the swinging needle-carrying arm 82 having at its free end the split needle-clamp 83 in which is secured by means of the fastening screw 84 the shank of the curved lower needle 85 with laterally grooved blade in which are disposed two eyes 85' and 85'' of which one is near the point and the other near the enlarged shank portion, as represented in Figs. 6 and 11. The needle-clamp 83 is shown provided with a guide-eye 83' through which the lower thread is led from the upper end of the hollow rod 56 to the needle-eye 85'' and thence to the needle-eye 85' (Fig. 11). Intermediate its ends, the needle-carrying arm carries the ball-stud 86 embraced by a strap at the upper end of the pitman 87 whose lower end is provided with

a similar strap embracing a similar stud 88 extending laterally from the head 57 of the rod 56, as represented particularly in Figs. 1 and 6. By the described independent connections of the looper and the lower needle with the head 57 of the actuating rod 56 these lower stitch-forming elements are given their respective simultaneous operative movements in different angularly disposed planes relative to each other and to the path of reciprocation of the upper needle 37.

The turret-disk 59 is formed on its upper face and at one side with the bearing boss 89 in which is journaled the fulcrum stud-screw 90 extending laterally from an upwardly extending post 91 having a transversely channelled head 92 upon which is secured the foot 93 of a bent arm 94 having the offset needle-plate 95 with crescent-shaped needle aperture 96 of which one end receives the straight upper needle and the other receives the curved lower needle. The needle-throat is adapted to be tilted upon its fulcrum-stud 90 to permit the advance of the cutting mechanism to operative position, and is normally maintained in operative relation with the stitch-forming mechanism by means which are or may be constructed as represented in my said United States Patent No. 1,048,786.

The lower-needle thread *t* is in practice led from the source of supply through the tension device 97 and thence through suitable thread-eyes in the spaced parallel members of the thread-guide 98 whose foot 99 is adjustably secured upon the bracket-plate 101 by means of the fastening screw 100, from which thread-eyes it is led upwardly through the rod 56 and thence through the guide-eye 83' to the lower needle 85. To the head 52 of the plunger-bar 53 is secured by means of the fastening screw 101 the shank 102 of a flat pull-off finger 103 having a path of movement intermediate the spaced members of the thread-guide 98 and adapted in its lower position to form a bend in the lower thread intermediate the tension and the work so as to draw the previously formed lower-thread loop up to the work and pull a supply of lower thread through the tension for the succeeding stitch-forming cycle, as represented in Fig. 4.

The upper rotary shaft 10 is shown provided with a cam-cylinder 104 provided with a two-stage cam-groove 105 entered by a roller-stud 106 upon the depending arm of a vibratory upper-thread take-up lever 107 fulcrumed at 108 upon the arm of the machine and adapted to act upon the needle-thread intermediate the upper tension device 109 and the upper needle, once for each stitch-forming cycle. The upper thread is led, as usual in this type of buttonhole stitching machines, from the tension

through the eye of the take-up lever and thence downwardly through the hollow needle-bar to the needle.

In the operation of the stitch-forming mechanism as thus described, the upper needle 70 descends through the material *m* to its lowest position while the actuating crank is still approaching its respective extreme lower position, and begins to rise to throw out a loop of its thread *n* just about as the said 75 actuating crank is at its lowest point. In the meantime, the looper-actuating crank 43 traverses the lower portion of its range of movement and thereby rapidly draws down the rod 56 which causes the quick movement 80 of the looper 73 to loop-seizing position, as represented in Fig. 8. As the crank 43 continues its movement, the toggle is bent to extreme position, as represented in Figs. 4 and 9, the looper being advanced in a curved 85 path around the needle and carrying the needle-thread loop to an inclined position between itself and the material and directly above the point of the lower needle (Fig. 12).

The continued movement of the looper-actuating crank 43 produces the rapid straightening of the toggle and initial entrance of the lower needle into the upper-needle thread-loop and its continued rise 95 through the needle-throat and the button-hole slit *s* in the material while the looper performs its retrograde movement. The lower needle reaches its extreme upper position and the looper its extreme retracted 100 position just as the toggle becomes straightened, but as the toggle members move slightly past straightened position, as represented in Fig. 3, the rod 56 receives a slight dip in its upper position which is 10. communicated to the lower needle to cause it to throw out a loop of its thread *t* above the work for entrance of the descending upper needle, as represented in Fig. 10, the looper being given a corresponding idle 11. movement adjacent its extreme retracted position. It will be observed that the lower needle performs its rapid advance movement in passing through the upper-needle thread-loop held by the looper, the function 111 of the dwell-producing action of the actuating toggle device being to interrupt its reciprocatory movement in its loop-presenting position wherein the lower thread is held for passage by the upper needle. In other 120 words, the function of the dwell-producing action of the toggle device is performed in conjunction with the lower needle in its loop-presenting capacity. The actions of the pull-off member 103 and the take-up 125 member 107 are timed to take place each while its respective needle is retracted from the work, so as to effectively set the stitches at the completion of each stitch-forming cycle.

Secured upon the lower side of the bracket-arm 3 by means of the screw 110 is a bracket in the form of a laterally extending yoke 111 between the spaced upper and lower members of which and fulcrumed upon the stud-pin 112 is the hub 113 of a swinging arm 114 carrying the toothed sector 115 meshing with the pinion 38 of the rotary needle-bar bushing. The hub 113 has 10 extending therefrom at an angle with the arm 114 a second and shorter arm 116 carrying the stud-screw 117.

Into the bearing boss 118 bolted to the base member 1^a to sustain the main-shaft 6 is tapped the shouldered stud-screw 119 affording a fulcrum upon which is fitted the hub 120 of a swinging arm 121 carrying at its outer end the toothed sector 122 meshing with the toothed pinion 63 applied to the hub 58 of the turret. From the hub 120 extends in angular relation with the arm 121 a second arm 123 carrying the stud-screw 124.

Disposed adjacent the standard 2 and 25 near the forward side of the machine frame is the vertical rock-shaft 125 journaled near its upper end in the bearing bracket 126 projecting from the standard 2 and having also a suitable bearing in the base 1. This 30 rock-shaft has secured upon its upper and lower ends, respectively, the lateral crank-arms 127 and 128. The former carries a stud-bolt 129 embraced by the apertured extremity of one section 130 of a two-part link 35 having another section 131 whose apertured extremity embraces the stud-screw 117 of the crank-arm 116. The sections 130 and 131 of the link are adjustably secured to the connecting plate 132 by means of screws 133 40 entering elongated apertures in said plate and tapped into the link sections, respectively. By this means the compound link thus formed is lengthwise adjustable for determining the correct position of the toothed 45 sector 115 and the circular position of the needle 37 relatively to the looper mechanism.

The crank-arm 128 carries at its extremity the stud-bolt 134 embraced by the apertured extremity of one section 135 of a two-part link having another section 136 whose apertured extremity embraces the stud-screw 124 of the crank-arm 123. The sections 135 and 136 of this link are adjustably secured 55 to the connecting plate 137 by means of screws 138 entering elongated apertures in said plate and tapped into the link sections, respectively, similarly to the upper sectional link, and for the same purpose in relation 60 to the circular position of the turret and the lower stitch-forming elements sustained thereby.

The crank-arm 128 carries intermediate its ends a roller-stud 139 entering the cam-groove 140 in the lower face of the feed- 65

wheel 141 by means of which the rock-shaft 125 is turned to impart reverse rotary movements to the needle-bar bushing 32 and the turret 59, and hence to the stitch-forming elements sustained by them respectively, in 70 stitching the ends of the button-hole.

The feed-wheel derives its step-by-step rotary feeding movements from clutch mechanism similar to that of my United States Patent No. 862,125, of August 6, 1907, 75 and comprising clutch-dogs 142 embracing the depending flange 143 of the feed-wheel and actuated by the vibrating operating lever 144. The lever 144 is adjustably connected with one end of a link 145 whose opposite end is attached to the vibratory lever 146 fulcrumed at 147 and carrying a roller-stud entering the cam-groove 148 of the cylinder 149 fixed upon the main-shaft 6. As in the machine forming the subject of 80 my said Patent No. 1,024,490, the feed-wheel derives from the clutch mechanism above described, a partial rotation during the stitching operation, the rotation being completed by the action upon its periphery 85 of the reciprocating pawl-bar 150.

The work-holder comprises the longitudinally traveling and sidewise movable lower clamp-plate 151 and the clamping feet 152 carried by the arms 153 pivotally 90 mounted upon the block 154. The work-holder derives its operative movements relatively to the stitch-forming mechanism from suitable cam-grooves in the upper face 95 of the feed-wheel through connections with 100 swinging levers 155 and 156 carrying roller-studs entering said cam-grooves, as shown more fully in my United States Patent No. 1,039,241, of September 24, 1912.

As shown more particularly in my said 105 Patent No. 1,048,786, the traveling cutting mechanism comprises the upper cutting member 157 sustained by the cutter-bar 158 and acting in conjunction with a lower cutting member carried by the cutter-bar 159. 110 These cutter-levers are mounted upon a common fulcrum sustained by the traveling block 160 and are actuated by the transverse cutter-shaft 161 driven by a belt embracing the loose belt-wheel 162 with a suitable intermediate clutch device through the action of which the cutter-shaft is given a rotation at the beginning of a buttonhole stitching operation.

As represented in the drawings, the cutting mechanism is disposed lengthwise of 120 the machine and in alignment with the path traversed by the lower needle in its reciprocating movements through the buttonhole slits. As so disposed, the cutting device has 125 a range of movement intermediate the fulcrum-studs 112 and 119, the stitch-mechanism turning rock-shaft 125 being arranged in the rearward part of the machine and at one side of the center where it is entirely 130

clear of the cutting mechanism and other operative parts which may be assembled or removed independently of such rock-shaft and the mechanism which it actuates.

- 5 The fulcrum-pin 16 of the stop-lever 15 has secured thereon the forwardly projecting arm 163 carrying the roller 164 which is adapted for engagement by the cam-plate 165 upon the can-wheel 166 fixed upon the 10 cutter-shaft 161 by means of which the stop-motion may be set for the stitching operation at the completion of a buttonhole cutting action, as shown in my said Patent No. 1,024,490; and the stop-motion is adapted 15 to be thrown into stopping position by the action of the spring 167 upon the stop-lever in conjunction with a tripping point upon the feed-wheel acting upon the rock-lever 168 operatively connected with a detent-lever 20 for the stop-lever arm 163, the action of the stop-motion in arresting the stitch-forming mechanism serving through suitable connections to throw the pawl-bar 150 into operative relation with the feed-wheel 25 for completing the rotation of the latter.

As thus described, the machine is set in motion for performing a buttonhole-producing operation by initiating the rotation of the cutter-shaft which causes the cutting elements to travel into stitching position and to close upon the work and to then recede to initial retracted position, after which the stop-motion is tripped to start the stitching mechanism. The stitching now proceeds as before described, the stitching elements being given a semi-rotation at the eyelet-end of the buttonhole slit and being turned into initial position at the completion of the stitching operation at the narrow end of the 40 buttonhole. This stitching proceeds very rapidly by reason of the actuation of all the stitching elements from rotary cranks with simple intervening connections avoiding all harsh movements. The mounting of the toggle device for the lower stitch-forming elements independently of the turret obviously not only insures the utmost simplicity in the construction of such device, but avoids the needless loading of the turret and insures 45 its lightness in weight for quick and accurate step-by-step rotary movement in the stitching of the end or ends of a buttonhole, depending upon the character of the latter.

In the embodiment represented in the drawings, the timing of the operative movements of the cutting device, the work-feeding mechanism and the stitch-mechanism turning device is similar to that of my Patent No. 1,024,490, the return rotation of the 50 stitch-forming mechanism to initial position being effected by the movement of the feed-wheel subsequent to the stitching operation under the action of the pawl-bar 150; but it is obvious that the present improvements are 55 equally adapted to machines constructed for

operation similarly to that of my pending application Serial No. 776,506, filed June 30, 1913.

It is evident that the looper mechanism herein shown and described, while designed particularly for embodiment in that class of buttonhole stitching machines in which the stitch-forming mechanism rotates in the stitching of the eye of the buttonhole, is not limited in its adaptation to any particular type of machine, and that it is susceptible of considerable modification in its construction and arrangement of parts within the scope of the present invention. It is also obvious that certain features of this invention are adapted for use independently of the others, and that they are susceptible of change under different working conditions without departure from the invention.

Having thus set forth the nature of the invention, what I claim herein is: —

1. In a sewing machine, in combination, a reciprocating needle, turning means therefor, a turret, means for turning it in unison with the needle, a loop-presenting element mounted thereon and coöperating with said needle, an actuating crank, a toggle device mounted independently of the turret and operatively connected with said loop-presenting element, and an operative connection between said crank and the toggle device.

2. In a sewing machine, in combination, a reciprocating upper needle, turning means therefor, a turret, means for turning it in unison with said needle, a reciprocating lower needle and a looper mounted upon said turret and each coöperating with the other and with the upper needle in the production of stitches, an actuating crank, a toggle device mounted independently of the turret and operatively connected with the lower needle and looper, and an operative connection between said crank and the toggle device.

3. In a sewing machine, in combination, a reciprocating needle, a coöperating loop-presenting element, a rotary support therefor, means for turning said needle and support in unison, a reciprocating actuating rod operatively connected with said loop-presenting element, a toggle device sustained independently of said support and connected with and imparting to said rod endwise movements with a dwell at one end of its range of movement, an actuating crank, and an operative connection between said crank and the toggle device.

4. In a sewing machine, in combination, a reciprocating upper needle, turning means therefor, a lower needle coöperating with said upper needle, a rotary turret upon which said lower needle is mounted, means for turning said turret in unison with the upper needle, a reciprocating actuating rod

operatively connected with said lower needle and disposed in substantially axial relation with the turret, a toggle device connected with and imparting to said rod endwise movements with a dwell at one end of its range of movement, an actuating crank, and a link connection between said crank and the toggle device.

5. In a sewing machine, in combination, a reciprocating upper needle, turning means therefor, a lower needle coöperating with said upper needle, a rotary turret upon which said lower needle is mounted, means for turning said turret in unison with the upper needle, a reciprocating actuating rod operatively connected with said lower needle and disposed in substantially axial relation with the turret, a toggle device mounted independently of said turret and connected with and imparting to said rod endwise movements with a dwell at one end of its range of movement, an actuating crank, and a link connection between said crank and the toggle device.

25. In a sewing machine, in combination, a reciprocating needle, and a coöperating loop-presenting element mounted for movement in a path substantially lengthwise of said needle for passage through the work, a reciprocating actuating rod operatively connected with said loop-presenting element, an actuating crank, a swinging lever, a link connection between said lever and the reciprocating rod, and a link connection between said crank and lever adapted to communicate to said lever movements into and out of alinement with its link connection with said rod.

7. In a sewing machine, in combination, a reciprocating needle, turning means therefor, a loop-taking element coöperating with said needle, a rotary turret sustaining said loop-taking element, means for turning said turret in unison with said needle, a reciprocating actuating rod journaled in said turret and operatively connected with said loop-taking element, an auxiliary reciprocating rod mounted independently of said turret and having a swivel connection with said actuating rod, an actuating crank, a swinging lever, a link connection between said lever and the auxiliary reciprocating rod, and a link connection between said crank and lever adapted to communicate to said lever movements into and out of alinement with its link connection with said auxiliary rod.

8. In a sewing machine, in combination, a reciprocating needle, and a coöperating thread-carrying loop-taking element, means for turning them in unison, spaced thread-guides for the thread leading to said loop-taking element, a reciprocating actuating rod operatively connected with said loop-taking element, a toggle device connected

with and imparting to said rod endwise movements with a dwell at one end of its range of movement, a pull-off member connected with said rod and movable in unison therewith between said thread-guides, and actuating means for said toggle device.

9. In a sewing machine, in combination, a reciprocating needle, turning means therefor, a loop-taking element coöperating with said needle, a rotary turret sustaining said loop-taking element, means for turning said turret in unison with said needle, a reciprocating actuating rod operatively connected with said loop-taking element and turning with said turret, a toggle device mounted independently of said turret, a swivel connection between a member of said toggle device and said actuating rod, spaced stationary thread-guides for the thread leading to said loop-taking element, a pull-off finger operatively connected with said toggle device and reciprocating in unison with said actuating rod, and actuating means for said toggle device.

10. In a sewing machine, in combination, a reciprocating eye-pointed upper needle, turning means therefor, a lower needle coöperating with said upper needle, a carrier therefor, a rotary turret, means for turning the same in unison with said needle, a fulcrum for said carrier mounted upon said turret and disposed at substantially the level of the eye of the upper needle when in loop-presenting position, a reciprocating actuating rod journaled within and axially of said turret, a link connection between said rod and the lower needle-carrier, a toggle device mounted independently of said turret and operatively connected with said rod, an actuating crank, and an operative connection between said crank and the toggle device.

11. In a sewing machine, in combination, a reciprocating eye-pointed upper needle, turning means therefor, a lower needle and a looper coöperating with said upper needle and with each other in the production of stitches, a rotary turret sustaining the lower needle and looper, means for turning the turret in unison with the upper needle, a reciprocating actuating rod, an operative connection between said actuating rod and the lower needle, a connection independent thereof between the actuating rod and the looper, a toggle device mounted upon a stationary support, a connection between said toggle device and the actuating rod for imparting to the latter endwise movements having a dwell at one end of its throw, and actuating means for said toggle device.

12. In a sewing machine, in combination, a reciprocating needle, a loop-taking element coöperating with said needle, an oscillatory crank connected with and communicating operative movements to said loop-taking element, a reciprocating actuating rod, driving

means including a spirally-toothed gear and an internally grooved nut slidably fitted thereto one of which is connected with and reciprocated by said actuating rod and the other operatively connected with said crank, and means for imparting endwise movements to said actuating rod.

13. In a sewing machine, in combination, a reciprocating needle, a loop-taking element coöperating with said needle, an oscillatory crank connected with and communicating operative movements to said loop-taking element, a reciprocating actuating rod, driving means including a spirally-toothed gear and an internally grooved nut slidably fitted thereto one of which is connected with and reciprocated by said actuating rod and the other operatively connected with said crank, a toggle device for imparting endwise movements to said actuating rod, and actuating means for said toggle device.

14. In a sewing machine, in combination, a reciprocating needle, a loop-taking element coöperating with said needle, a swinging arm upon which said loop-taking element is pivotally mounted, an oscillatory crank pivotally connected with the looper independently of its connection with said swinging arm, a reciprocating actuating rod, driving means including a spirally-toothed gear and an internally grooved nut slidably fitted thereto one of which is connected with and reciprocated by said actuating rod and the other operatively connected with said crank, and means for imparting endwise movements to said actuating rod.

15. In a sewing machine, in combination, a reciprocating upper needle, a lower needle and a looper coöperating with said upper needle and with each other in the production of stitches, a carrier for the lower needle, a fulcrum for said carrier, a carrier for said looper, a swinging arm upon which the looper-carrier is pivotally mounted, an oscillatory crank pivotally connected with the looper-carrier independently of its connection with said swinging arm, a spirally-toothed gear connected with said crank, a reciprocating member having a spirally-grooved aperture slidably fitted upon said gear, a link connection between said member and the lower needle-carrier, and means for imparting to said member reciprocating movements in a direction lengthwise of said gear.

16. In a sewing machine, in combination, a reciprocating upper needle, turning means therefor, a lower needle and a looper coöperating with said upper needle and with each other in the production of stitches, a rotary turret, turning means therefor, a carrier for the lower needle, a fulcrum for said carrier sustained by and inclined to the axis of movement of said turret and upon which

the lower needle is adapted to move in a plane slightly inclined to the path of the upper needle, a carrier for said looper, a swinging arm upon which the looper-carrier is pivotally mounted, a fulcrum for said arm parallel with the axis of movement of said turret, an oscillatory crank pivotally connected with the looper-carrier independently of its connection with said swinging arm, a spirally-toothed gear connected with said crank and movable upon an axis parallel with that of said turret, a reciprocating member having a spirally-grooved aperture slidably fitted upon said gear, a link connection between said member and the lower needle-carrier, and means for imparting to said member reciprocating movements in a direction parallel with the axis of the turret.

17. In a sewing machine, in combination, a needle, a rotary support therefor provided with a toothed pinion, complementary loop-taking means, a rotary support therefor provided with a toothed pinion, toothed sectors each meshing with one of said pinions, independently mounted fulcras for said sectors, an actuating rock-shaft disposed parallel with said fulcras and provided with a plurality of cranks, turning means for said rock-shaft, and link connections between said cranks and said toothed sectors, respectively.

18. In a sewing machine, in combination, a needle, a rotary support therefor provided with a toothed pinion, complementary loop-taking means, a rotary support therefor provided with a toothed pinion, toothed sectors each meshing with one of said pinions, independently mounted fulcras for said sectors, an actuating rock-shaft disposed parallel with said fulcras and provided with a plurality of cranks, turning means for said rock-shaft, and endwise adjustable link connections between said cranks and said toothed sectors respectively.

19. In a buttonhole sewing machine, the combination with the frame comprising a base and an overhanging bracket-arm, of a reciprocating needle, a rotary support therefor journaled in the bracket-arm and provided with a toothed pinion, loop-taking means coöperating with said needle in the production of overseam-stitches, a rotary support therefor journaled in said base and provided with a toothed pinion, a button-hole cutting device comprising a cutter-carrying lever disposed intermediate the base and bracket-arm and in substantial alinement with said needle, toothed sectors each meshing with one of said pinions, fulcras for said sectors mounted respectively in the base and the bracket-arm above and below said cutter-carrying lever, an actuating rock-shaft journaled at opposite ends in the base and the bracket-arm beyond the range

- of movement of said cutter-carrying lever, and link connections between said cranks and said toothed sectors, respectively.
20. In a sewing machine, in combination, 5 a reciprocating needle-bar, an upper needle carried thereby, a lower needle and a looper coöperating with said upper needle and with each other in the production of stitches, a uniformly rotating actuating crank, operative 10 connections between said crank and said lower needle and looper, a uniformly rotating shaft, a needle-actuating crank thereon rotating in unison with the first-named crank, and a pitman connected with 15 said needle-actuating crank and with said needle-bar at a point offset from a diameter of the circular path of movement of the needle-actuating crank parallel with said needle-bar.
21. In a sewing machine, in combination, 20 a reciprocating needle-bar, an upper needle carried thereby, loop-taking means comprising an oscillatory looper adapted to seize thread loops from the upper needle at one side of the work and a reciprocating lower needle adapted to carry a thread-loop through the upper-needle thread-loop and present it for passage of the upper needle at the opposite side of the work, a uniformly 25 rotating actuating crank, a toggle device operatively connected with said crank and having independent connections with said looper and lower needle, a uniformly rotating shaft, a needle-actuating crank thereon 30 rotating in unison with the first-named crank, and a pitman connected with said 35
- needle-actuating crank and with said needle-bar at a point offset from a diameter of the circular path of movement of the needle-actuating crank parallel with said needle-bar. 40
22. In a buttonhole stitching machine, the combination with the frame comprising a base and an overhanging bracket-arm, of parallel upper and lower rotary shafts journaled respectively in the base and the bracket-arm, operative connections between said shafts whereby they are rotated in unison, overseaming stitch-forming mechanism comprising a rectilinearly reciprocating needle, a coöperating needle reciprocating in a path at an acute angle therewith, and a looper adapted to seize a loop from one of said needles and spread it for passage of the other needle, speed-accelerating 45 connections between one of said shafts and one of said needles and between the other of said shafts and the other of said needles and the looper, imparting to said needles and looper operative thread-engaging movements of the same frequency and to each movements of greater frequency than the rotations of its respective shaft, and a stop-motion device for controlling the operation 50 of the moving parts of the machine. 55
- In testimony whereof, I have signed my name to this specification, in the presence of two subscribing witnesses.
- EDWARD B. ALLEN.
